COVER-FEEDING MECHANISM

Willy H. Diezel, Fairfield, Conn., assignor to The Max Ams Machine Company, Bridgeport, Conn., a corporation of New York

Application May 11, 1949, Serial No. 92,624

1 Claim. (Cl. 113—114)

1

This invention relates to cover-feeding mechanisms for seaming machines, and has for its main object the production of self-contained cover-feeding means that can be readily attached to an already existing type of machine (for use at neighborhood centers rather than in canning factories) lacking such means.

In the accompanying drawings, the invention is disclosed in a concrete and preferred form, in which:

Fig. 1 is a top plan view of the cover-feeding mechanism;

Fig. 2 is a view in front elevation, partly broken away and in section, looking in the direction of arrow 2 of Fig. 1;

Fig. 3 is a view similar to Fig. 1, but with some of the parts removed;

Fig. 4 is a perspective diagrammatic view of the cover-separating knives, the cover-feeding slide, and associated elements;

Fig. 5 is a transverse sectional view, substantially on the plane of line 5—5 of Fig. 1;

Fig. 6 is a longitudinal sectional view, substantially on the plane of line 6—6 of Fig. 1, showing the cover-feeding slide engaging a separated cover; and

Figs. 7, 8, 9 and 10 are diagrammatic views, showing different steps in the operation of separating and feeding the covers.

In automatic seaming machines, cans and covers are fed automatically to a seaming station, and successive seaming cycles of the machine occur at regular intervals. There is another type of machine, generally referred to as "semi-automatic," in which the cans and covers are not fed automatically, and in which successive seaming cycles occur at irregular intervals at the will of the operator. That is to say: the operator, after placing a can and a cover in the machine, steps on a treadle or moves a handle, thereby elevating the can and cover into the plane of the seaming tools and at the same time initiating a single seaming cycle which, when completed, does not repeat itself and only begins again at the will of the operator when he again steps on the treadle. The problem this invention seeks to solve is to so construct an automatic cover-feeding mechanism as to make it operative in connection with a seaming machine having irregularly occurring seaming cycles at arbitrary intervals. It will be apparent that, to free the operator from the necessity of handling a cover each time a seaming operation is to be performed, will tend to shorten the interval between irregularly occurring seaming operations.

The seaming station of the machine is indicated at 20, and 21 is a cover-receiving or supporting ledge to support a cover 22. 23 is the usual pedestal for supporting a can 24 which, when elevated by the pedestal, rises through opening 25

2

of the seaming station, lifts cover 22 from supporting ledge 21 and brings the assemblage into the plane of the seaming tools of seaming machine 26 in a well-known manner. 27 indicates the cover supply station, having the usual four posts 28 to contain a stack of covers 27a. 29 indicates a raceway over which a cover 22 separated from stack 27a is carried to supporting ledge 21 of the seaming station. 30 is a reciprocatory cover-feeding slide, moving in guides 31, and operated continuously by any suitable means such as rotating gear 32 having a crank 33 connected by links 34 and 35 to rockshaft 36, which latter is connected by links 37 and 38 to cover-feeding slide 30. 39 and 40 indicate a pair of oppositely arranged cover-separating knives. One of these, 39, is carried by a rocker lever 41, mounted to rock on pivot 42. 43 indicates a second rocker lever on which cover-separating knife 40 is carried, said rocker lever 43 being longer than rocker lever 41 and being mounted to rock on pivot 44. 45 indicates an actuator-link, pivotally connected at 46 and 47 to rocker levers 41 and 43. Carried by cover-feeding slide 30 is a cam 48 to be engaged by a cam roller 49, mounted on actuator-link 45. A spring 50 anchored on pin 51 of the framework, and connected to actuator-link 45 at 46 urges cam roller 49 into engagement with cam 48 of cover-feeding slide 30. 52 is a detector-finger carried by rocker lever 43 adjacent cover-receiving ledge 21 of the seaming station, and it will be observed that the pull of spring 50 will tend to cause said detector-finger 52 to overlie cover-receiving ledge 21 if no cover is present on said cover-receiving ledge. Also that, if a cover is present on cover-receiving ledge 21, said detector-finger will move outwardly and thereby tend to oppose the action of spring 50.

Turning now our attention to the diagrams 40 Figs. 7 to 10 inclusive, the operation of the cover-feeding mechanism will be described in detail. Considering first Fig. 7, it will be seen that cover-feeding slide 30 is in its retracted position in rear of cover stack 27a, that cam roller 49 is in engagement with low portion 48a of cam 48, that no cover is present on cover-receiving ledge 21 of the seaming station, and that spring 50 is exerting its force unopposed by detector-finger 52, thereby causing cover-separating knives 39 and 40 to disengage the stack of covers so that said stack is lowered to rest on raceway 29. As cover-feeding slide 30 advances from the position shown in Fig. 7 to that shown in Fig. 8, it will be seen that cam roller 49 has traveled up the incline of cam 55 48, to high portion 48b and has thereby exerted sufficient pressure on actuator-link 45 to cause cover-separating knives 39 and 40 to enter the stack of covers above the lowermost one, thereby elevating the remainder of the stack and releasing the lowermost cover. This occurs before

cover-feeding slide 30 engages the lowermost cover. This action of cam roller 49 and cam 48 will also have withdrawn detector-finger 52 very slightly from its projection over cover-receiving ledge 21. Cover-feeding slide 30 continues its motion engaging the lowermost and separated cover 22, and will move the same over raceway 29 and onto cover-receiving ledge 21 at the seaming station, as shown in Fig. 9. The presence of the cover on cover-receiving ledge 21 moves detector-finger 52 outwardly, and this motion is transmitted through rocker levers 41 and 43, and actuator-link 45, to cause cover-separating knives 39 and 40 to still more deeply enter the stack of covers, as indicated in Fig. 9, and also to cause cam roller 49 on actuator-link 45 to be lifted out of the plane of cam 48. Cover-separating knives 39 and 40 continue to hold the stack of covers elevated while cover-feeding slide 30 returns to a position where it passes beneath and in rear of the stack of covers. If the operator has stepped on the treadle, thereby causing the can to remove the cover from cover-receiving ledge 21, it will be observed that the parts of the cover-feeding mechanism will return to the position shown in Fig. 7 and the cycle will be repeated. If, however, the operator has not stepped on the treadle and cover 22 remains on cover-receiving ledge 21, then the effect will be that shown in Fig. 10, in which it will be seen that cam roller 49 remains elevated out of contact with cam 48, and that cover-separating knives 39 and 40 remain beneath the stack so that the latter is not lowered to raceway 29. This condition will continue so long as cover 22 remains on cover-receiving ledge 21, and cover-feeding slide 30 will continue to traverse back and forth without feeding any covers. When cover 22 is again removed from cover-receiving ledge 21 by a raised can 24, the previous condition will be restored and another cover will be fed from the cover supply station to cover-receiving ledge 21.

It is pointed out that, prior to the time when the parts occupy the position shown in Fig. 7, cover-feeding slide 30 was traveling on its return stroke, cam roller 49 was in engagement with high portion 48^b of the cam, and therefore cover stack 27^a was held elevated by cover-separating knives 39 and 40, and no cover was resting on raceway 29 at cover supply station 27.

Considering the operation of the device in terms of the action of cover-feeding slide 30, it will be observed that said slide makes its excursions or reciprocates back and forth at regular intervals; that, at the end of its return stroke of one excursion, after it has passed beneath and in rear of cover stack 27^a, it causes, by reason of the engagement of cam roller 49 with low portion 48^a of cam 48 and the pull of spring 50, the cover-separating knives to be withdrawn and the cover stack to rest on the raceway; and that at the beginning of its outward stroke, on its next excursion and before it reaches the cover stack, it causes, by reason of engagement of cam roller 49 with high portion 48^b of cam 48, the cover-separating knives to engage the stack above the lowermost cover and to elevate the remainder of the stack so that said slide 30 can feed the released and separated lowermost cover to the seaming station. It will further be observed that, if a cover is present on cover-receiving ledge 21 at the time slide 30 reaches the end of its return stroke, detector-finger 52 will hold cam roller 49 out of contact with cam 48 and therefore the

cover stack will not be lowered at the end of the return stroke of slide 30.

It will be seen that the cover-feeding mechanism is self-contained and self-regulating, so to speak, and can readily be attached to an existing "semi-automatic" seaming machine by simply bolting the attachment to the framework of said machine, and by providing a constantly driven gear, such as 32, to operate the cover-feeding slide.

I claim:

In a cover-feeding mechanism having a cover supply station to contain a stack of covers that are to be fed, one by one, over a raceway to the cover-receiving ledge of the seaming station of a single-cycle seaming machine: a reciprocatory cover-feeding slide, traveling in the same plane when moving in either direction, to move a separated cover from the cover supply station over the raceway to the cover-receiving ledge of the seaming station of the seaming machine; means to reciprocate said cover-feeding slide to make excursions at regular intervals from a point in rear of the stack of covers to the seaming station and back again; a pair of cover-separating knives located opposite to each other at the cover supply station to simultaneously act to separate the lowermost cover from the stack of covers by engaging and elevating the remainder of the stack, and to lower the stack to the raceway by simultaneously disengaging said stack; two pivotally supported rocker-levers, one carrying one and the other carrying the other, of said cover-separating knives; a spring-pressed actuator-link located adjacent and in rear of the cover supply station and pivotally connected at its opposite ends to said rocker-levers; a cam roll carried by said actuator-link; a cam carried by the cover-feeding slide to engage the cam roll on said actuator-link to bring the cover-separating knives into and out of engagement with said stack of covers; a detector finger, carried by one of said rocker-levers, extending to the cover-receiving ledge and constructed and arranged to overlie the cover-receiving ledge when said cover-separating knives are disengaged from the stack of covers, said detector finger when pushed outwardly by the edge of a cover on the cover-receiving ledge to react on the actuator-link to cause the latter to move the cover-separating knives into engagement with the stack of covers and to move the cam roll out of engagement with the cam; and a spring to urge said actuator-link in a direction to cause said cover-separating knives to disengage the stack of covers, to cause said detector finger to overlie the cover-receiving ledge and to urge said cam roll into contact with said cam.
